UNITED STATES PATENT OFFICE.

JOHN T. BENTLEY, OF ENGLEWOOD, NEW JERSEY, ASSIGNOR, BY MESNE ASSIGNMENTS, TO THE LUCIFORM COMPANY, OF NEW YORK.

PHOTOREPRODUCTION PROCESS.

SPECIFICATION forming part of Letters Patent No. 632,436, dated September 5, 1899.

Application filed May 26, 1897. Renewed September 26, 1898. Serial No. 691,948. (No specimens.)

To all whom it may concern:

Be it known that I, JOHN T. BENTLEY, a subject of the Queen of Great Britain, residing in Englewood, in the county of Bergen and State 5 of New Jersey, have invented certain new and useful Improvements in Photoreproduction Processes, of which the following is a specification.

This invention relates to the art of photoreproduction, and more particularly relates to an improved process of reducing the visual area of matter to the required size without the destruction, disintegration, or elimination of portions of the reproduced original, whereby 15 the legibility thereof is retained and whereby also such reduction may be readily obtained without the necessity of first securing a printed original or copy thereof.

A primary object of the invention is to provide a simple and efficient process by means of which matter for reproduction, more especially typographic composition or letter-press matter, may be directly reproduced of the required size and a correctly-engraved 25 plate, gelatin film, lithographic stone, or other positive obtained without having, as heretofore generally required in this art, to first secure a printed original or "copy" of such matter.

30 A further object of the invention is the provision of an improved process of obtaining a printing surface or plate directly from an original without the necessity of using or first setting up type to secure a printed copy or 35 impression thereof and which original comprises characters, figures, or letters having such structural formation that they are particularly efficient for photoreproduction.

A still further object of the invention is to 40 furnish for the purpose of carrying out this process an object or character with such structural formation that when properly placed in position it will be without appreciable shadow around the same or with such structural formation that when placed in position for reproduction by this improved process not only 45 may shadows be eliminated, but a regular increased light or luminant zone may be obtained entirely around the same, whereby 50 such reproduced matter will be brought out

on the positive plate in a very clear and brilliant manner and whereby owing to the structural formation of such object an increased reduction as compared with the reduction of matter by the process now commonly in use 55 may readily be obtained while retaining the legibility thereof.

In the drawings accompanying and forming part of this specification, Figure 1 is a view of one form of typographic matter in position to be reproduced and shows the rays of light so directed thereon that a luminant zone is obtained around the elements composing such matter. Fig. 2 is a diagrammatic vertical sectional view taken in line *a a*, Fig. 1, 60 and shows on an enlarged scale one of the typographic characters of said figure and also illustrates the manner in which the luminant zone is formed around the same. Fig. 3 is a side elevation of the view shown in Fig. 1. 70 Fig. 4 is a view of another form of typographic matter in position similar to that shown in Fig. 1. Fig. 5 is a diagrammatic vertical sectional view taken in line *b b*, Fig. 4, and shows on an enlarged scale one of the typographic 75 characters shown in said figure and also illustrates the manner in which the luminant zone is obtained around the same. Fig. 6 is a side elevation of the view shown in said Fig. 4.

Similar characters of reference designate 80 corresponding parts in the different figures of the drawings.

In photoreproduction processes as usually carried out it is the practice first to set up in "forms" the type of the letter-press or other 85 matter to be reproduced and then obtain therefrom or from a printing-surface produced therefrom an impression or printed original or copy, which copy is then reproduced of the required size, within certain limits, by 90 photography and the use of the ordinary camera, in order to produce the positive plate from the negative so obtained. It has been found, however, that when such matter has been reproduced of a comparatively small 95 size the matter is imperfect, this being due mainly to the diminution and the disintegration of the letters, owing, as I believe, to the fact that the type-faces (and of course the impressions therefrom) are imperfect, unnat- 100

ural, and unbalanced in their structure, as such type-faces are ordinarily constructed with thick and hair lines, and hence they lack proper construction, so that in the process of reproduction the thinner parts or the hair lines of the impression-letters are cut out or bridged over by the light, thus leaving the thicker or larger parts separate and independent of each other. This imperfection, however, is also due to the apparent impossibility of increasing the clearness and brilliancy of the reproduced matter on the positive plate as compared with the original matter subjected to reproduction, so that owing to the disintegration and also to this lack of proper brilliancy (under the usual and old process) the greater the degree of reduction the grayer the reproduced matter becomes. Hence when this imperfectly-reproduced matter is placed before the eyes it tends to injure them. I have found, however, that objects formed by nature may be reduced to that stage where although imperceptible to the naked eye, yet when subjected to the microscope they are seen to be as clear and brilliant and as perfect as the original and without grayness of appearance or appreciable disintegration or diminution of form. This I apprehend is due to the structural formation of such natural objects, and therefore it follows that matter which has structural or bodily form (by which I mean matter that has structure or body as contradistinguished from a mere surface representation thereof) may be more perfectly reduced than that which has but a simulation thereof, and as a type impression or printed original or copy is but a simulation or resemblance to the type-faces it cannot be as perfectly reduced as if the elements or letters comprising the same had structural form. Yet it would be impossible, so far as practicability is concerned, to photoreproduce the original "form" of type, for while the type have structural form of a certain kind, although imperfect, it would be impossible not only to avoid the shadows which such type would cast intermediate and around each other, and which shadows would result in transparent or light lines on the negative, and consequently in dark or black lines on the positive plate, but in such reproduction the spaces and leads and also the metal forming the background of the type-faces would also be reproduced. Not only this, but the resultant reproduction would be white or gray letters on a black background, and it will be obvious that it would be practically impossible to rout out such matter in order to secure a perfect plate.

The main object of the invention is therefore to provide typographic or letterpress matter having such structural formation, however obtained, that it may be directly reproduced, thereby dispensing with the use of type and type-impressions, and consequently dispensing with such indirect method of reproduction heretofore practiced.

From the foregoing it therefore follows that

matter which is given such a structural formation that when properly placed in position will be without appreciable shadow around the same or is given such a structural formation that shadows will be eliminated and a regular increased light or luminant zone obtained around the same, similar to that which, it is apprehended, is around objects of nature, may be reduced to the same extent and with the same perfection as such natural objects and without disintegration or diminution thereof—that is to say, the visual area of such matter may be reduced without the destruction or elimination of any portion of the reproduced original. Therefore to obtain a reproduction of matter in which the elements composing the same may not only be of great brilliancy and clearness, but may also hold their form to whatever stage of reduction they are subjected and not become disintegrated, as heretofore, whereby such matter can be reduced to a greater degree than hitherto and yet be clearer and more legible than matter which is reduced under the old process to a lesser degree, and whereby it will be obvious that by this process pages or other forms of matter may be much smaller and at the same time clearer and more legible, is one of the objects of this improved process.

In carrying out this process in one way I provide the matter (which is to be reproduced) with structural form as contradistinguished from a mere simulation or surface representation of form (which latter is the case of an impression obtained from type) and have given this matter such structural formation that when properly subjected to the action of light appreciable shadows around the same are avoided and in some forms thereof an increased and intensified light or luminant zone is secured in place of such normal shadow region, whereby I am enabled to reproduce such matter with perfection and with great clearness and brilliancy, and consequently reduce the same to a far greater extent than can be done with imperfectly-formed matter or that which is but a simulation thereof.

As a preface to a further description of this improved process it will be understood that while I have herein shown typographic characters, such as letters of the alphabet, as comprising the elements of the matter to be reproduced the process can be carried out in connection with any object which can be given structural form, and therefore within the scope of this invention is considered any matter or object which can be given such structural formation that when properly placed in position will be without appreciable shadow around the same, and also any matter, images, or objects which can be given such structural formation that when subjected to the action of light shadows will be eliminated around the same and in place thereof a luminant zone obtained. Furthermore, it will be understood that any desired instrumentality or means may be used for

supporting these objects or elements in position, whereby they can be subjected to the other or reproduction steps of the process.

In carrying out the first step of this improved process one or more characters or objects, shown herein as typographic characters, such as letters, are disposed or assembled in position to form the matter to be reproduced, whereby they constitute the original.

5 Each of these letters, however, is so constructed, in one form thereof herein shown and described, that it has a reflecting border or edge entirely around the same (designated in a general way by 2) and which border or

10 edge is disposed to direct the rays of light onto the zone immediately adjacent to such letter, and thereby illuminate said zone and by reason of such illumination intensify the clearness of the outline of the letter itself

15 20 when reproduced by photography. In the species of typographic characters shown herein this reflecting border or edge is disposed in a general direction inclined to the plane in which the letter itself is located, and in

25 25 that form thereof shown in Figs. 1, 2, and 3 said general direction is downward and outward from the upper plane or top surface of said body, whereby such border will usually be of a curved form, as 3, so as to vary the re-

30 sultant angles of reflection in different portions of the luminant zone, and thereby produce a highly-effective action of the light upon the letter and the illuminated plane or surface 4, on which such letter is placed. In

35 35 the form of letter shown in Figs. 4, 5, and 6 the general direction of the border or edge surface 2 of the letter is downward and inward from its face or outer surface, being so disposed with relation thereto that rays of

40 40 light directed thereon from a sidewise position will be reflected from said border surface onto the plane or surface on which the letter is located, and in practice it is deemed desirable to have in this form of typographic

45 45 character the reflecting edge surface thereof made of a concave construction, as 5, so as to centralize the reflected rays in the relatively narrow zone immediately back of the extreme edge 6 of said letter, and thereby produce a

50 50 very greatly intensified illumination for the purpose of defining in the photographic negative, and thereby in the positive, the extreme edge of said letter or character in the sharpest manner possible. From the foregoing it

55 55 will therefore be seen that owing to the structural formation of the letters—as indicated, for instance, in Fig. 2—when the rays of light are properly directed thereon they will strike the curved or inclined outer sur-

60 60 face or border 3 of the letter and thence are deflected and diffused at varying angles onto different portions of the area immediately adjacent to the border or edge of such letter, whence they are reflected back, thereby form-

65 65 ing an intensified light or luminant zone 7 entirely around the letter, at the normal shadow region thereof, and hence completely

eliminating such shadow. Owing to this great diffusion and reflection of light immediately adjacent to the border of the character it will 70 be seen from an inspection of said Fig. 2 that instead of a shadow a greatly-intensified light is obtained, varying in degree and becoming less as the angle of reflection becomes greater, whereby such luminant zone 7 gradually 75 merges into the usual light area or surface 8 of the letter-support 10, at that point thereof where the reflected rays from such border cease, so that it will be seen that adjacent to the letter, which would ordinarily be the 80 normal shadow region thereof, the light is more intense and brilliant than at a remote distance therefrom, so that when reproduced on the negative, and consequently on the positive, the outline of the letter is sharp and 85 clear and is not disintegrated or diminished. From a view of Fig. 5 it will be seen that the same result takes place as the rays of light striking the inclined or concaved edge or border surface 5 of the letter are diffused therefrom and in a similar manner to that above 90 described form a luminant zone 7 entirely around the letter, the reflected rays being centralized in the relatively narrow zone immediately back of the outer edge 6 of such 95 letter, whereby a greatly-intensified illumination is obtained, that part of the luminant zone substantially in alignment with the line of sight (by the extreme edge of the letter) being the most brilliant, such zone gradually 100 merging into the light area 8, intermediate the letters or characters.

According to one mode of carrying out this improved process any required number of typographic characters or letters are organized or assembled in position in any desired way, such as by securing them adjacent to or on a support or supporting-surface, as 10, having an illuminable surface 8, which may constitute the light area or space intermediate the letters and on which the luminant zone 7 adjacent to the letters may be formed, whereby such letters constitute the matter to be reproduced. The matter so assembled is then subjected to light in such manner as to 110 directly illuminate the edges of the letters, whereby owing to the peculiar structural formation of such letters a brilliant and intense light or luminant zone 7 is obtained around the same, thereby eliminating shadow and securing in place thereof an intensified or brilliant light. The matter is then photographically reproduced and a negative formed, which negative is then treated in the usual or any suitable manner to form a positive or 115 printing surface, the letters of which will be found to have held their form without disintegration or diminution to whatever degree the same may have been reduced and will have a superior brilliancy and clearness 120 throughout.

It will be remembered that in utilizing for the purpose of making a printing-surface the photographic reproduction, which is made di-

rectly from the original matter, the photographic film is laid on the usual emulsion upon the plate, whereupon the plate is exposed to light, which, acting through the film, 5 hardens the emulsion in accordance with the character of the photographic reproduction on the film. One of the peculiar advantages of my present invention is that by making the photographic reproduction from original 10 matter in relief, having the characters thereof surrounded by a zone of relatively intense light, whereby the outlines of the characters are sharply defined in the photographic film, the emulsion is affected in a more clear 15 and definite way, so that the light during the light-printing operation will harden the emulsion to a greater extent than usual and so that the line of the hardening will be sharply defined, giving to the characters a very clear 20 and distinct outline. The film being now sponged in the usual manner, the surface of the film is then inked to bring out and protect those portions thereof which have been hardened by the action of the light, after 25 which the plate is washed off to remove all the superfluous portions of the film covering the spaces between the characters and so leaving the surface of the plate itself properly bared ready for subjection to the acids. The 30 result is that the outlines of the characters in the film having been so sharply defined by means of the relatively intense illumination immediately around the characters during the making of the photographic film the 35 edges of the characters in the film become perfectly continuous and smooth in outline, so that the protective ink when applied thereto lies smoothly thereon in perfect correspondence with the true form of the characters, and thereby furnishes an accurate outline 40 for the character-portion-protecting film when the plate is subjected to the etching operation, whereby there is produced a printing-plate having the characters thereon extremely perfect in outline and true reproductions on such scale of reduction as may be required of the original matter.

From the foregoing it will be seen that by means of this improved process matter can 50 be reduced to a greater degree than heretofore without the formation of dark or black lines on the positive plate and without the elements or parts of such matter becoming disintegrated—that is to say, the visual area 55 of the matter can be reduced without the destruction or elimination of any part of the reproduced original and which reduced matter will be of greater brilliancy and clearness than matter which has been subjected under 60 the old process to a lesser degree of reduction—from which it follows that under the present process less space is necessary than heretofore for the production of such matter. In other words, owing to the clearness and 65 brilliancy and the perfect formation of such reproduced matter, whereby the same is more legible even when reduced to a far greater

degree than heretofore, less space is necessary to contain the same. The result is that books containing a given amount of matter 70 on a page may be made with much smaller pages without unfavorably affecting the readability of the matter, thus giving to the volume a greatly-reduced size and making it possible to bring many standard works containing a relatively large amount of matter 75 down to the size of pocket editions, besides reducing the cost for paper, printing, binding, &c., in a corresponding proportion. Hence in addition to the other advantages of this 80 improved process is that of decrease in space as well as of material, and consequently a reduction in the cost of producing engraved, lithographic, or analogous matter.

In conclusion, among the many other advantages is that of directly producing a printing surface or plate from an original not formed from type, thereby dispensing with type and its appurtenances, and consequently the enormous expense thereof, especially since 90 by this process from the one original may be secured various sizes of reproductions, whereas when type is used different sizes of such type are necessary to secure different sizes of reproductions.

The term "character" as used in the claims is intended to include within its scope such designs, marks, symbols, letters, elements, or figures and the like as are adapted to be given the structure set forth, and the term "luminant zone" as used in the claims includes within its scope a zone of light or light of apparently increased intensity as compared with the appearance of the light adjacent to such zone, and the term "border" includes within its scope an edge, boundary, or outline.

I claim as my invention—

1. That improvement in the art of photoreproduction, which consists in assembling in position matter in relief to be directly reproduced; then subjecting the matter in relief to the action of light in such manner as to directly illuminate parts thereof and avoid shadow around the same, whereby a luminant zone is obtained around such matter in relief, and the matter thereby more sharply defined; and then subjecting the matter to photoreproduction, thereby to obtain a reproduction having the outlines of the reproduced matter sharply and clearly defined.

2. That improvement in the art of photoreproduction, which consists in assembling in position relatively to each other, adjacent to a supporting-surface, a plurality of characters in relief to be directly reproduced; then subjecting the characters to the action of light in such manner as to directly illuminate the edges of such characters and avoid shadow around the same, whereby a zone of relatively intense light is obtained around each character, and the character thereby more sharply defined; and then subjecting the matter to photographic reproduction, thereby to obtain a negative having the outlines of

the reproduced characters sharply and clearly defined.

3. That improvement in the art of photoreproduction, which consists in assembling in position relatively to each other, upon an illuminable supporting-surface, a series of typographic objects constituting the matter to be directly reproduced, each typographic object having structural formation; then subjecting the matter to the action of light, in such manner as to directly illuminate the edges of such objects and avoid shadow around the same, whereby a luminant zone is obtained upon such supporting-surface around each object; and then subjecting the matter to photographic reproduction, thereby to obtain a negative having the outlines of each object sharply and clearly defined.

4. That improvement in the art of photoreproduction, which consists in assembling in position relatively to each other a series of typographic elements in relief to be directly reproduced; then subjecting the typographic elements to the action of light, in such manner as to directly illuminate the edges of such elements and avoid shadow around the same, whereby a zone of relatively intense light is obtained upon such supporting-surface around each element; then subjecting the elements to photographic reproduction, thereby to obtain a negative having the outlines of each element sharply and clearly defined; and then utilizing such negative to form a positive having the typographic elements thereof of a relatively clear and perfect form and outline.

5. That improvement in the art of photoreproduction, which consists in assembling on an illuminable supporting-surface original matter to be reproduced, formed of characters having reflecting-borders; then subjecting such matter to the action of light from a direction to form illuminated zones around the characters by reflecting the light from said borders thereof; then photographing the matter so illuminated to produce a photographic negative; and finally printing through such negative onto a surface or plate and etching the plate to form a printing surface or plate, whereby the printing-plate will be produced with characters of a relatively clear and perfect form and outline, substantially as set forth.

6. That improvement in the art of photoreproduction, which consists in assembling in position characters constituting the matter to be reproduced, each of which characters is provided with a structural border; then subjecting the characters to the action of light in such manner as to illuminate the borders thereof and avoid shadow around the same, whereby a luminant zone is obtained around and adjacent to each character; and then subjecting such characters to photoreproduction, thereby to obtain a reproduction having the outlines of the reproduced characters sharply and clearly defined.

7. That improvement in the art of photoreproduction, which consists in assembling in position adjacent to an illuminable supporting-surface a plurality of characters constituting the matter to be directly reproduced, each of said characters having a relatively-inclined border; then subjecting the matter to the action of light in such manner as to directly illuminate the inclined border of such characters and avoid shadow around the same, whereby a zone of relatively intense light is obtained upon such supporting-surface around each character; then subjecting the matter to photographic reproduction, thereby to obtain a negative having the outlines of the reproduced characters sharply and clearly defined; and then utilizing such negative to form a positive.

8. That improvement in the art of photoreproduction, which consists in assembling in position adjacent to an illuminable supporting-surface characters constituting the matter to be reproduced, each of said characters having a curved inclined border; then subjecting said characters to the action of light in such manner as to directly illuminate the curved borders thereof and avoid shadow around the same, whereby a luminant zone is obtained upon such supporting-surface around each character; then subjecting the matter to photographic reproduction, thereby to obtain a negative having the outlines of the reproduced characters sharply and clearly defined; and then utilizing such negative to form a positive.

9. That improvement in the art of photoreproduction, which consists in disposing on an illuminable supporting-surface typographic characters constituting the matter to be reproduced, each of said characters having a convexed border extending around and located within the outer boundary-line thereof, whereby such border constitutes, when subjected to light, a reflecting medium; then subjecting the characters to the action of light in such manner as to directly illuminate the convexed borders of said characters and avoid shadow around the same, whereby a luminant zone is obtained upon such supporting-surface around each character; then subjecting the matter to photographic reproduction, thereby to obtain a negative; and then utilizing such negative to form a positive.

10. That improvement in the art of photoreproduction, which consists in assembling in position characters in relief constituting the matter to be reproduced, each of which characters is provided with a structural border; then subjecting the characters to the action of light in such manner as to illuminate the borders thereof and avoid shadow around the same, whereby a luminant zone is obtained around and adjacent to each character; then subjecting such characters to photoreproduction, thereby to obtain a reproduction having the outlines of the reproduced characters

sharply and clearly defined; and then utilizing such reproduction to form a printing-surface.

11. That improvement in the art of reproduction, which consists in assembling in position, and avoiding appreciable shadow around the same, structurally-formed characters to constitute the original to be reproduced; and then reproducing such original to form a reproduction and avoiding the formation of superfluous marks around such reproduction.

12. That improvement in the art of reproduction, which consists in assembling in position, and avoiding appreciable shadow around the same, characters in relief having a structural border, and constituting the original to be reproduced; and then reproducing such original to form a reproduction without the formation of superfluous marks around such reproduction.

13. That improvement in the art of reproduction, which consists in assembling in position, and avoiding appreciable shadow around the same, structurally-formed characters to constitute the original to be reproduced; then reproducing such original to form a reproduction and avoiding the formation of su-

perfluous marks around such reproduction; and then utilizing such reproduction to form a printing surface or plate likewise without superfluous marks around the reproduced original.

14. The herein-described art of reproduction, which consists in removably assembling in position for direct reproduction an original comprising a plurality of structurally-formed characters constituting the letterpress matter to be reproduced; and then reproducing such matter and avoiding the formation of superfluous marks around such reproduced original.

15. The herein-described art of reproduction, which consists in removably assembling in position for direct reproduction an original comprising a plurality of structurally-formed characters having a structural border and constituting the letterpress matter to be reproduced; and then reproducing such matter and avoiding the formation of superfluous marks around such reproduced original.

JOHN T. BENTLEY.
